CLAIM

The ornamental design for a stand for transporting and permitting work on motors, as shown and described.

DESCRIPTION

FIG. 1 is a side elevational view of a support stand for permitting work on motors showing my design; FIG. 2 is an end elevational view; and FIG. 3 is a perspective view wherein a second support stand and a motor are shown in dotted lines to illustrate normal use.

Fig. 3.

Fig. 2.

Fig. 1.
